(57) **CLAIM**

The ornamental design for a table, as shown and described.

DESCRIPTION

FIG. 1 is a front perspective view of a table embodying my new design with a first playing surface on the top of the table;

FIG. 2 is a front perspective view of the table embodying my new design with a second playing surface rotated to the top of the table;

FIG. 3 is a top plan view;

FIG. 4 is a bottom plan view;

FIG. 5 is a front elevational view, the rear being a mirror image thereof; and

FIG. 6 is a left side elevational view, the right being a mirror image thereof; and,

FIG. 7 is a perspective view of an alternate embodiment of the table embodying my new design having a square shape.

1 Claim, 5 Drawing Sheets
